UNITED STATES PATENT OFFICE.

ERNST H. ELZEMEYER AND PAUL S. KNITTEL, OF ST. LOUIS, MISSOURI.

APPARATUS FOR PRODUCING, SEPARATING, AND FEEDING POWDERED COAL.

Application filed August 1, 1921. Serial No. 468,800.

To all whom it may concern:

Be it known that we, ERNST H. ELZEMEYER, a citizen of the United States, and a resident of the city of St. Louis, in the 5 State of Missouri, and PAUL S. KNITTEL, a former subject of the former Emperor of Germany, who has signified his intention of becoming a citizen of the United States, and a resident of the city of St. Louis, in the 10 State of Missouri, have invented a new and useful Improvement in Apparatus for Producing, Separating, and Feeding Powdered Coal, of which the following is a specification.

15 This invention relates principally to apparatus for producing, separating and feeding powdered coal wherein the powdered coal is produced in a rotary grinder and is removed therefrom and fed to the furnace 20 by means of air currents.

One of the principal objects of the present invention is to provide a simple and efficient means for regulating the air currents, whereby a fuel of the desired fineness and 25 quantity may be obtained. Other objects are to increase the output of powdered coal, to eliminate the use of dust collectors heretofore commonly used, to simplify the construction and to reduce the cost of manufacture and operation. The invention consists in the construction, arrangement and 30 combinations of parts hereinafter described and claimed.

In the accompanying drawing, which 35 forms part of this specification, and wherein like symbols refer to like parts wherever they occur,

Fig. 1 is a vertical section through an apparatus embodying our invention; and 40 Fig. 2 is a perspective view of the shutter-valve for regulating the air current.

Referring to the accompanying drawing, our apparatus comprises a rotary grinder preferably in the form of a ring pulverizer 45 comprising a casing 3 whose end walls rotatably support a shaft 4 having longitudinally spaced spiders 5 keyed thereon. The radially extending arms of the spiders 5 are connected at their outer ends by a series of 50 radially spaced parallel rods 6. Loosely supported on the rods 6 are grinding rings 7, which cooperate with the concave grinding surface of the casing to pulverize the material.

55 The upper portion of the front wall of the casing 3 has a material inlet opening

8 which communicates with the lower end of the feed chute of a hopper 9; and said chute is provided with a gate 10 for cutting off the flow of the material to the grinder. 60 If desired an automatic feed hopper of the kind shown in Knittel Patent No. 1,318,389 dated October 14, 1919, may be substituted for the hopper shown.

The top wall of the casing is provided 65 with an outlet opening 11 which communicates with the lower end of a vertically disposed pipe 12. Arranged between the material inlet opening 8 and the outlet opening 11 is an apron or deflector in the form of an 70 inclined plate 13, whose lower front edge is hinged to the front wall of the casing 3 adjacent to the upper edge of said inlet opening. The front edge of the apron 13 terminates adjacent to the curved rear wall of 75 the casing 3. The front edge of the apron is adapted to cooperate with the inner surface of the curved portion of the rear wall of the casing to cut off communication between the pipe 12 and the grinding area of 80 the casing 3 or to form an opening therebetween of varying width, the width of said opening depending on the angular position of the apron, which swings in an arc whose radius is less than the radius of the curved 85 portion of the casing. The apron is adjusted by means of a sector 14 which has one end fixed to said apron. The free end of the sector extends through a slot in the rear wall of the casing 3 and is provided with a series 90 of holes adapted to receive a pin whereby the apron may be supported in the desired adjusted position. The apron 13 is provided, adjacent to its lower hinged end, with an opening 15, the purpose of which 95 will hereinafter appear.

The upper end of the pipe 12, which leads from the top of the casing 3, opens into the lower end of an expansion or separating chamber in the form of a casing 16 of larger 100 area than the pipe 12. The upper end of the expansion chamber communicates with the lower end of a pipe 17, whose upper end opens into a fan-blower 18, and said fan, in turn, is provided with a pipe 19, which leads 105 to the furnace (not shown).

Within the uppermost pipe 17 is located a control valve comprising counterpart half-shutters in the form of hollow tapering half-cones 20 whose lower ends are substantially 110 semicircular and are hinged together and whose upper ends terminate in a point. The

curved half sections 20 are pivotally supported in the pipe by the pivots 21, which hingedly secure said sections together, and are provided with sector arms 22 similar to the sector arm 14 of the apron 13, whereby said halves may be separated or brought together to control the flow of air and material through the passageway in the pipe 17. The fan is provided with a suitable air valve 22^a, whereby air may be supplied to the fan to reduce the suction created thereby in the passageway 23 formed by the pipe 12, expansion chamber 16 and pipe 17.

The expansion chamber 16 is preferably provided with a hinged apron or deflector plate 24 having an actuating sector 25. This apron is hinged to the front wall of the chamber, which is provided with an inclined sacking spout 25^a. The lower end of said spout is closed by means of a cap 26. An auxiliary hopper 27 has an inclined spout which opens into the expansion chamber through the rear wall thereof at a point opposite to the apron 24. This auxiliary hopper is adapted to receive powdered coal delivered thereto in sacks from the sacking spout 25 and is provided with a gate 28 for cutting off the flow of the powdered coal to the expansion chamber.

The operation of the apparatus is as follows: Lump coal is fed by the hopper 9 to the rotary grinder where it is engaged by the rotating rings 7 and is pulverized. During the grinding operation the greater part of the pulverized coal is thrown upward by the circular motion of the rings against the inclined apron or deflector 13, which causes the particles to drop back into the path of the rotating rings 8. The larger particles that pass through the opening between the apron and the casing fall back upon the upper surface of the downwardly inclined plate 13 and drop through the opening 15 near the hinged end of the apron into the path of the rotating rings. The suction created by the fan 18 in the passageway 23 causes the finer particles of coal to be drawn through the opening between the free edge of the apron 13 and the curved portion of the casing 3 and thence through the lowermost pipe 12 into the expansion chamber 16. This expansion chamber, by reason of its larger area, has the effect of decreasing the velocity of the air currents produced by the suction of the fan 18, thereby causing the heavier particles to fall back into the grinder. The fine particles are then drawn upwardly through the shutter-valve 20 into the fan 18 and are delivered thereby through the pipe 19 to the furnace. The valve 20 serves as a baffle and can be adjusted to permit only the finest particles to enter the fan. This valve also controls the amount of fine dust permitted to enter said fan. The size and quantity of pulverized material per-

mitted to enter the expansion chamber 16 is regulated by adjusting the hinged apron or baffle plate 13.

During the operation of the apparatus, the apron 24 within the expansion chamber may be lowered to nearly close said chamber, thereby forming a pocket in which the fine coal dust will be collected. This dust is then drawn off through the spout 25 into sacks and deposited in the auxiliary feed-hopper 27. With this arrangement, in the event of an accident to the pulverizer, the gate 28 in the spout of the auxiliary feed-hopper 27 can be opened, and the reserve material therein used without interfering with the operation of the apparatus.

Obviously, the invention admits of considerable modification without departing from the invention; therefore, we do not wish to be restricted to the particular forms and arrangements shown in the drawing.

What we claim is:

1. An apparatus of the kind described comprising a grinding device having an inlet opening and an outlet opening, a feed-hopper communicating with said inlet opening, a passageway leading from said outlet opening, and suction means for creating an air current in said passageway, and a control valve located in said passageway said valve comprising a plurality of curved V-shaped plates whose base portions are hinged together, whereby said plates are adapted to be separated and brought together to control the flow of air and material through said passageway.

2. An apparatus of the kind described comprising a pulverizing device having an inlet opening and an outlet opening, a feed-hopper communicating with said inlet opening, a passageway leading from said outlet opening, suction means for creating an air current in said passageway whereby the pulverized material is withdrawn from said pulverizing device through the passageway, said passageway having an enlarged portion between said outlet and said suction means, whereby the fine material upon reaching the enlarged portion of said passageway is separated from the coarse material which drops back into said pulverizing device, and a hinged plate located between the grinding area of said pulverizing device and the outlet opening thereof, said hinged plate being adapted to cut off communication between said passageway and said pulverizing device or to form an opening therebetween of varying width, said hinged plate having an opening therein adjacent to the hinged side thereof for returning the coarse material to the grinding area of said pulverizing device.

3. An apparatus of the kind described comprising a pulverizing device having an inlet opening and an outlet opening, a feed-hopper communicating with said inlet open-

ing, a passageway leading from said outlet opening, suction means for creating an air current in said passageway, whereby the pulverized material is withdrawn from said pulverizing device through the passageway, said passageway having an enlarged portion between said outlet and said suction means, whereby the fine material upon reaching the enlarged portion of said passageway is separated from the coarse material which drops back into said pulverizing device, and adjustable means located in said passageway between said chamber and said suction device constituting a regulator for the air current, a deflector for the heavier material and a cut-off for the passageway, said adjustable means comprising a pair of curved V-shaped plates whose base portions are hinged together and are pivotally supported within said passageway.

4. An apparatus of the kind described comprising a grinding device, having an inlet opening and an outlet opening, a feed-hopper communicating with said inlet opening, a passageway leading from said outlet opening, suction means for creating an air

current in said passageway, whereby the pulverized material is withdrawn from said grinding device through the passageway, said passageway having an enlarged portion 30 between said outlet and said suction means, whereby the fine material upon reaching the enlarged portion of said passageway is separated from the coarse material which drops back into said pulverizing device, an auxiliary feed-hopper communicating with the enlarged portion of said passageway, a sack- 35 ing spout leading from said enlarged portion, and a hinged deflector located in said enlarged portion adjacent to said sack- 40 ing spout, said deflector being adapted to form a pocket in which the pulverized material is collected, whereby said material is adapted to be drawn off through said spout and deposited in said auxiliary feed-hopper and 45 constitutes a reserve supply of pulverized material.

Signed at St. Louis, Missouri, this 29th day of July, 1921.

ERNST H. ELZEMEYER.
PAUL S. KNITTEL.
